HERBERT N. MASSEY, OF BERKELEY, CALIFORNIA.

GAME.

Application filed September 21, 1925. Serial No. 57,735.

My present invention relates to games, and it has for one of its objects the provision of a game of educational value and particularly one which is amusing and which will create interest and develop ability in arithmetic.

The game of this invention is played on a board with marbles which are shot by one or more players from playing areas into a field having obstacles such as pins projecting above the surface of the board, and having depressions in the surface of the board adapted to lodge the marbles, each of said depressions preferably being labeled with a numeral having prefixed thereto one of the signs of the four fundamental operations of arithmetic, namely, addition, subtraction, multiplication and division.

Another object of the invention is the construction of a field on the playing board which will present a great variety of shots of varying difficulty.

Other objects will be apparent from the following description. The game board of the present invention is illustrated in the accompanying drawings in which

Figure 1 is a plan view of the game board, and

Figure 2 is a sectional view taken on line 2-2 of Figure 1.

Referring to the drawings for more detailed description thereof, A represents a square, flat board having a raised rim or border B therearound. Triangular marble pockets C are formed at the corners of the board by partitions D extending between adjacent sides of the border B. A pin E projects above the board at the center thereof. A five-pointed star F may be drawn on the board, the center of this star being the center of the board. Other pins project above the surface of the board, and these pins are here shown as arranged on circumferences of concentric circles having their center at the center of the board, and being designated simply by circles. The innermost circle on which pins are arranged has its circumference passing through the apexes of the reentrant angles formed by the lines of the star F, and pins G are arranged on the circumference at the apex of the reentrant angles. A second circle may have its circumference passing through the points of the star, and pins H are positioned at these

points. Other pins H are positioned on the circumference of the second circle and at the intersection thereof with radii passing through the centers of the pins G. A third circle has pins J positioned on its circumference, this circle circumscribing a square which circumscribes the second circle. The pins J are positioned on the third circle at points where the circumference of the latter intersect radii which pass through the pins G and pins H. A fifth and outermost circle has pins K positioned on its circumference, this circle circumscribing a square which circumscribes the third circle. The pins K are positioned on the fifth circle at points where the circumference of the latter intersect radii which pass through pins G and H. A fourth circle has pins L positioned on its circumference which is between the third and fifth circles. The pins L may be positioned in staggered relation to the pins K. The pins L may be disposed with relation to the pins J and K, for example, when the diameter of the third and fifth circles are respectively fourteen and twenty inches, the pin 1^L may be one and one-half inches from the pin 1^K on a line drawn from 1^K to 1^J and the pin 2^L may be one and one-half inches from 2^K on a line drawn from 2^K to 2^J and the other pins L may be disposed in the same relation with reference to adjacent pins J and K.

A depression may be made in the board adjacent each pin and these depressions are preferably behind the pins relative to views taken on radii passing through the pins looking toward the center pin. These depressions are represented in the drawing by circles surrounding semi-circles and are labeled with the same letters as their corresponding pins but with the subscript 1 attached to the letters. In addition to the mentioned depressions I also preferably provide depressions G² which are located adjacent the pins G and outside the star F. The depressions are variously numbered with numerals ranging from one to ten and each of these numerals is prefixed with one of the signs of the four fundamental processes of arithmetic, viz, addition, subtraction, multiplication and division. A square M circumscribes the outermost circle and the four spaces numbered 1 to 4 with Roman numerals, between the outermost circle and

the square M, constitute shooting areas, to which areas the players are confined when shooting marbles into the field within the outermost circle.

5 The game is played as follows: The game may be played by from one to four players, preferably by four, two players playing opposite each other as, for example, the positions 1 and 3, and the other pair of players 10 being at positions 2 and 4. The players agree upon a certain number as, for example, 100, as the goal of the game, the side obtaining this score first winning the game. Each 15 player has preferably ten marbles allowing him ten shots, one shot at a time, playing round in turn. All the marbles of a given player are of the same color and are different in color from the marbles of the other players. At the end of a series of ten rounds, 20 the player next in order from the one who played first in the previous series has first shot or play. A shot is made by a player supporting a marble by placing the first finger of his left hand upon the marble in 25 a horizontal position and snapping the marble with the second finger of his right hand. In shooting the marbles, the object is to lodge one's own marbles in the depressions marked plus or multiply, or shoot those of 30 the opponent's out of the depressions marked plus or multiply; and also to shoot one's own marbles out of depressions marked minus or divide and to shoot the marbles of one's opponents into the depressions marked 35 minus or divide.

It will be readily seen that the marbles for the most part will not be lodged directly in the depressions but only after rebound or carom from the pins. The marbles which 40 are shot into the field, that is, into the outermost circle, should not be moved except by a shot from a player's marble or until the end of a series of ten rounds. After a series of ten rounds, the score is obtained for each 45 pair of partners by making arithmetical calculations called for by depressions holding the marbles. Additions are made first, then subtractions, then multiplications, and finally divisions. For example, if one player 50 has six marbles in depressions at the end of the series of ten rounds, and these marbles are in depressions numbered +3, +10, +2, -1, $\times 5$, $\div 7$; the additions are made first, in which instance the additions equal 55 the sum of 15; the one is then subtracted from the 15, leaving 14, which is then multiplied by 5, making 70, which is divided by 7, leaving 10. This is the score contributed by one player. The process is the same, of course, for each player. If desired, fractions of one-half or more resulting from division 60 may count as one point.

From the foregoing arithmetical calculations, it will be readily appreciated that it is 65 to a player's advantage to lodge his own

marbles in depressions marked plus or multiply; to shoot his marbles out of depressions marked minus and divide, and to shoot his opponent's marbles out of depressions marked plus or multiply, or into depressions 70 marked minus or divide.

From observation of the arrangement of numerals on the board, it will be seen that the numerals are so distributed that neither 75 pair of partners has an advantage over the other pair.

While I have described one embodiment of my invention, it is obvious that modifications may be made therein without departing from the spirit of the same. For example, other arrangements of pins and depressions may be devised but the arrangement 80 herein shown is now preferred.

I claim:—

1. In a marble game, a flat board having 85 depressions in its upper surface, and pins adjacent the depressions, said depressions being labeled with numbers and with symbols of the fundamental processes of arithmetic. 90

2. In a marble game, a flat board having depressions in its upper surface, and pins adjacent the depressions, said depressions being labeled with numbers and with symbols of the fundamental processes of arithmetic, said depressions and pins being arranged on the circumferences of concentric 95 circles. 100

3. In a marble game, a flat board having depressions in its upper surface, and pins adjacent the depressions, said depressions being labeled with numbers and with symbols of the fundamental processes of arithmetic, said pins being arranged on the circumferences of concentric circles. 105

4. In a marble game, a flat board having depressions in its upper surface, and pins adjacent the depressions, said depressions being labeled with numbers and with symbols of the fundamental processes of arithmetic, said pins being arranged on the circumferences of concentric circles, the circumference of one of the circles passing through the points of a star, the center of which coincides with the centers of the concentric circles. 110

5. In a marble game, a flat board having depressions in its upper surface, and pins adjacent the depressions, said depressions being labeled with numbers and with symbols of the fundamental processes of arithmetic, and a pin at the center of the board. 115

6. In a marble game, a flat board having depressions in its upper surface, and pins adjacent the depressions, said depressions being labeled with numbers and with symbols of the fundamental processes of arithmetic, said pins being arranged on the circumferences of concentric circles, the circumference of one of the circles passing 120 125 130

through the points of a star, the center of which coincides with the centers of the concentric circles, and a pin at the center of the board.

5. 7. In a marble game, a flat board having depressions in its upper surface, and pins adjacent the depressions, said depressions being labeled with numbers and with symbols of the fundamental processes of arithmetic,

10. 10. said pins being arranged on the circumferences of concentric circles, where the mentioned circumferences intersect their radii which pass through the points and apexes of the reentrant angles of a star having its center coincident with the center of the board.

15. 8. In a marble game, a flat board having depressions in its upper surface, and pins adjacent the depressions, said depressions being labeled with numbers and with symbols of the fundamental processes of arithmetic,

20. 20. said depressions and pins being arranged on the circumferences of concentric circles, where the mentioned circumferences intersect their radii which pass through the points and apexes of the reentrant angles of a star having its center coincident with the center of the board.

25. 25. 9. In a marble game, a flat board having depressions in its upper surface, and pins adjacent the depressions, said depressions being labeled with numbers and with symbols of the fundamental processes of arithmetic,

30. 30. said pins being arranged on the circumferences of concentric circles, where the mentioned circumferences intersect their radii

which pass through the points and apexes of the reentrant angles of a star having its center coincident with the center of the board, said board having shooting areas adjacent the corners thereof.

10. In a marble game, a flat board having depressions in its upper surface, and pins adjacent the depressions, said depressions being labeled with numbers and with symbols of the fundamental processes of arithmetic, said depressions and pins being arranged on the circumferences of concentric circles, where the mentioned circumferences intersect their radii which pass through the points and apexes of the reentrant angles of a star having its center coincident with the center of the board, said board having shooting areas adjacent the corners thereof. 45

11. In a marble game, a flat board having depressions in its upper surface, and pins adjacent the depressions, said depressions being labeled with numbers and with symbols of the fundamental processes of arithmetic, said depressions and pins being arranged on the circumferences of concentric circles, said board having shooting areas adjacent the corners thereof. 50

12. In a marble game, a flat board having 60

12. In a marble game, a flat board having depressions in its upper surface, and pins adjacent the depressions, said depressions being labeled with numbers and with symbols of the fundamental processes of arithmetic, said board having shooting areas adjacent the corners thereof. 65
